UNITED STATES PATENT OFFICE.

FRANCISCO MASSILLON, OF MEXICO, MEXICO.

MACHINE FOR MOLDING TUBES.

No. 918,880.

Specification of Letters Patent. Patented April 20, 1909.

Application filed April 25, 1908. Serial No. 429,267.

To all whom it may concern:

Be it known that I, FRANCISCO MASSILLON, engineer, a citizen of Belgium, residing at 2^a Calle de San Lorenzo No. 19, Mexico city, 5 5 Federal district, Republic of Mexico, have invented new and useful Improvements in Machines for Molding Tubes, of which the following is a specification.

My invention relates to improvements in 10 machines for molding all kinds of tubes, and the objects of my invention are, first, to manufacture tubes by means of centrifugal force without employing molds of sand or clay, second to produce tubes without 15 cracks caused by the contraction of the material when it cools, third to provide tubes more evenly made. I attain these objects by the mechanism illustrated in the accompanying drawings, in which—

20 Figure 1. is a vertical view of the machine. Fig. 2. is a top view of the same. Fig. 3. is a longitudinal section of the mold. Fig. 4. is a transversal section on the line *a—a* Fig. 3. Fig. 5. is a section at the bearings of the 25 mold. Fig. 6. is a section on the line *b—b* Fig. 3. Fig. 7 is an end view of one of the metallic plates; Fig. 8 is a sectional view of said plate; and Fig. 9 is a perspective view thereof.

30 In all the figures similar numerals refer to similar parts.

Numeral 1 designates the divided tubular mold mounted on rollers 2, geared between the annular ribs 3, provided with the object 35 of establishing uniformity to the rotation of the mold when action is transmitted to the rectangular bar 4, from the adjustable motorwheel 5; and 6 designates the movable arms in which the upper rollers 2 are 40 placed said arms being lifted before the upper half of the mold is taken off by the hooks 7, in order to remove the tube.

Numerals 8. represents the funnel through which the cast material is led to the extremity of the mold, in which it will spread out in an even thickness under the centrifugal force by the rotation of the mold.

Numeral 16 represents a convenient arrangement for tightly closing the two halves 50 of the mold before the casting starts. For the purpose of avoiding cracks in the coupling of the tube 15 I employ annular cush-

ions 9 of clay, loam, terra cotta or any other suitable material, over which cushion I place a thin metallic plate 10 folded in such a way 55 that the two extremities overlap each other, to allow for expansion or contraction. At the end of the tubular mold is the stopper 11 with perforations 12 which coincide with perforations in the surrounding annular ring 13 60 of clay or loam, allowing gases and air to escape from the interior, and still further around the ring is a thin metallic plate 14 having its ends overlapping and similar to the plate 10 and with the same object of 65 making allowance for contractions of the cast material by cooling off. Plate 14 is shown in Figs. 7, 8 and 9. This is of greatest importance as formerly the casting of tubes in metallic molds presented difficulties in turning out a product without ruptures, but with 70 this present invention it will be overcome; though the first tube cast might not be as perfect as those made when the mold has been heated.

I claim:

1. A mold for molding tubes, comprising two semi-cylindrical portions, means for connecting said portions together, circular tracks formed on said portions, and a series 80 of rollers engaging in each of said tracks, the top roller being removable so as to permit the removal of one of the mold portions, substantially as described.

2. A mold comprising a cylindrical body 85 portion, a stopper for closing one of the ends of said cylindrical portions, an annular ring of clay forming part of said stopper, and a metallic expansible strip surrounding said annular ring, substantially as described. 90

3. A rotating mold for casting tubes by centrifugal force, comprising a stopper for closing one end of the mold, a metallic expansible strip or ring formed in the interior of the mold adjacent one end, and a cushion 95 of clay surrounding the exterior surface of the said strip, substantially as described.

In testimony whereof I have signed my name to this specification in the presence of two subscribing witnesses.

F. MASSILLON.
